UNITED STATES PATENT OFFICE.

JOSEPH G. ALLEN, OF RACINE, WISCONSIN.

HOSE-SUPPORTER.

1,169,757.

Specification of Letters Patent.

Patented Feb. 1, 1916.

Application filed October 19, 1914. Serial No. 867,401.

To all whom it may concern:

Be it known that I, JOSEPH G. ALLEN, a citizen of the United States, residing at Racine, in the county of Racine and State of Wisconsin, have invented certain new and useful Improvements in Hose-Supporters; and I do declare the following to be a full, clear, and exact description of the invention, such as will enable others skilled in the art 10 to which it appertains to make and use the same.

This invention relates to hose supporters.

The object of the invention is to provide a device of this character constructed to prevent the formation of varicose veins in the leg which are usually caused by interference with the free flow of the blood through the large vein on the inside of the leg produced by wearing tight garters.

20 This invention consists in providing a hose supporter with a curved vein-spanning member with which are connected the leg-encircling band and the hose-engaging elements.

25 With these and other objects in view, the invention consists of certain novel features of construction, combination and arrangement of parts as will be more fully described and claimed.

30 In the accompanying drawings; Figure 1 represents a side elevation showing this improved supporter applied; Fig. 2 is an enlarged front elevation thereof with the leg band broken off; Fig. 3 is a rear elevation 35 thereof with parts broken out; Fig. 4 is a transverse section thereof.

In the embodiment illustrated a transversely curved plate 1 is shown composed of metal or other suitable non-yielding material preferably metal. Vertically extending cushioning pads 2 are arranged on the inner face of this plate near its opposite side edges and are designed to prevent abrasion of the skin of the leg and to assist in holding the 45 curved central portion of the plate out of contact with the leg, which central portion is adapted to be positioned over the large vein on the inside of the leg when the device is in use and thus permit the blood to flow 50 through said vein without restriction and thereby prevent the formation of varicose veins. The plate 1 and pads 2 are inclosed

in a suitable covering *a*, preferably of a soft fabric, to give the device a neat appearance and to prevent the metal from being in direct contact with the leg of the wearer. As shown this plate 1 has its upper and lower edges curved inwardly as shown at 3 and 4 to reduce the size and weight of the plate, and to provide a narrow curved central portion 3'. One side of the plate is also shown curved inwardly at 5, thus providing four ears as 6 at the corners thereof. The outer edges 2' of the cushioning plates 2 conform in shape with the contour of the ends of the 65 plate 1.

Hose engaging elements 7 of any desired or suitable construction are secured to the covering *a* opposite the lower ears and a leg band 8 is secured at one end to the covering 70 *a* opposite one of the upper corners of the plate 1 preferably to the one adjacent the curved side of the plate. This leg band is preferably constructed of elastic material and is provided with the usual adjusting 75 buckle or clasp 9 for varying its length. It is also provided with a fastening element 10 adapted to coöperate with another element 11 secured to the covering opposite the outer face of the plate 1 at any desired or suitable 80 point whereby the leg band is detachably engaged with the plate for properly positioning the garter on the leg of the wearer.

From the above description the application of the device and its uses will be obvious 85 and it is therefore not thought necessary to go further into detail, the gist of the invention residing in forming means for protecting the large vein of the leg and preventing the garter from interfering with 90 the flow of blood therethrough.

I claim as my invention:

A hose supporter comprising a transversely curved rigid plate having its upper and lower edges curved inwardly to form 95 a narrow curved central portion and ears at the four corners thereof, upright cushioning pads secured to the inner face of said plate on opposite sides of its narrow curved central portion, the outer edges of said pads 100 conforming in shape with the contour of the ends of said plate, a fabric covering completely inclosing said plate and said pads, a leg encircling band secured to said cover

adjacent the ears on the upper edge of said plate and on the outer face thereof, and those engaging elements secured to said covering adjacent the ears on the lower edge of
5 said plate and on the outer face thereof, substantially as and for the purpose set forth.

In testimony whereof I have hereunto set

my hand in presence of two subscribing witnesses.

JOSEPH G. ALLEN.
